BY ATTORNEY

UNITED STATES PATENT OFFICE.

HARVEY N. GILBERT, OF BROOKLINE, MASSACHUSETTS, ASSIGNOR TO AMERICAN OPTICAL COMPANY, OF SOUTHBRIDGE, MASSACHUSETTS, A VOLUNTARY ASSOCIATION OF MASSACHUSETTS.

ELECTROPLATING.

1,246,083.

Specification of Letters Patent. Patented Nov. 13, 1917.

Application filed April 24, 1915. Serial No. 23,678.

To all whom it may concern:

Be it known that I, HARVEY N. GILBERT, a citizen of the United States, residing at Brookline, in the county of Norfolk and 5 State of Massachusetts, have invented certain new and useful Improvements in Electroplating, of which the following is a specification.

This invention relates to improvements in 10 means for and the method of electro-plating, and has for its primary object to reduce the time and cost of the plating operation to a minimum and to insure against any waste of the plating material.

15 Other objects as well as the advantages and improved features in the method of operation of the invention should be apparent from the following description taken in connection with the accompanying drawings, in which:

Figure I is a vertical longitudinal sectional view through the complete apparatus.

Fig. II is a horizontal sectional view on the line II-II of Fig. I.

25 Fig. III is a detailed vertical sectional view through one of the agitating fingers.

Fig. IV is a vertical sectional view through a slightly modified form of agitating finger.

Referring to the drawings by numerals, 30 wherein is illustrated the principle of the invention, 1 designates a receptacle or container of a non-conductive material, such as porcelain, glass, stone, or any other suitable composition, having near the upper edge 35 thereof on its inner face, an inwardly extending flange or rib 2. A second container 3 of a non-conductive material, such as porcelain, glass or the like, is placed within the container 1 and is held in spaced relation

40 thereto by means of the supporting rings 4 which are connected by the ribs 5 and which engage the rib 2 on the container 1 and a rib 6 on the container 3 for supporting the frame in its desired position. The container 45 3 is preferably provided with a plurality of perforations or apertures 7 whereby the electrolyte 8 which is placed in the container 1 will also flow to the interior of the container 3.

50 An anode 9 which may be a platinum, gold or carbon plate, or any other suitable substance, is disposed within the electrolyte 8 and is connected with a suitable source of electric current by means of the wire 10. It 55 will be readily understood that one or more

of the anodes 9 may be provided and that these anodes may be either placed within the receptacle 1 or within the receptacle 3, as has been illustrated in Fig. I of the drawings.

A cover 11 is provided for the container 3 and has extending therethrough a spindle 12 on the outer end of which is mounted the operating handle 13. While I have shown the handle 13 for rotating the spindle 12, 65 it will be understood that any other desired means may be employed for obtaining the rotation of the spindle, and, therefore, I do not wish to limit myself to any particular method of operation.

Secured to the lower end of the spindle 12 are a plurality of fingers 15 which are of a non-conductive material and which extend downward therefrom in staggered spaced relation. These fingers preferably have their 70 lower ends arranged in varying spaced distances from the bottom of the container so as to effectively agitate the articles to be plated upon rotation of the handle 13, and at the same time stir up and diffuse the 80 electrolyte 8, the articles to be plated being adapted to be placed in the container 3 so as to be engaged by the fingers.

The fingers 15, and spindle 12 are hollow and are adapted to receive the wires 16 85 which carry at their lower ends the cathode contacts 17.

Before proceeding with the description of the operation of the device just described it may be well to state some of the disadvantages of the apparatuses heretofore used for electro-plating, and some of the advantages which the present invention possesses there-over.

One of the most commonly used of the old 95 processes for electro-plating was to string the articles to be plated upon a suitable wire frame and to submerge the same with the articles thereon in the plating solution. It will be readily apparent that this was a very 100 tedious, time consuming and expensive operation, and possessed many disadvantages.

Another one of the generally used apparatuses for electro-plating was to provide a 105 basket of gauze or any other suitable material, in which the articles to be plated were placed, and to immerse the basket with the articles therein in the bath or solution until the same was suitably plated. One of 110

the great disadvantages of this process was in the case of plating with precious metal, the great loss due to the plating of the basket as well as the articles contained therein, and it will be readily seen that in the case of gold or silver the use of a basket a few times soon represented considerable value in plating material contained thereon.

By providing the receptacles 1 and 3 of the present invention of porcelain, glass or other non-conductive material, preferably having glazed surfaces, it will be readily understood that none of the metal in the electrolyte will be deposited thereon during plating of the article. It will be further understood that by the provision of the relatively small cathode contacts 17 which are the only surfaces on the apparatus on which the metal is plated, it will be seen that there is practically no loss or waste of the metal from the electrolyte through action in coating undesirable surfaces.

In operation the articles to be plated are placed within the container 3 and enough of electrolyte 8 placed in the container 1 so as to entirely cover all of the articles, as well as the anode. Current is then introduced through the wire 10 to the anode and the handle 13 then rotated, whereby the cathode 17 will engage certain of the articles to be plated, thus completing a circuit through the articles and the electrolyte so that the electric action upon the electrolyte 8 will cause the metal contained therein to be plated upon the varicus articles immersed therein, the staggering of the fingers 15 serving to at all times insure of at least one or more of the cathode contacts 17 being in engagement with the articles to be covered, and it will be readily understood that the articles themselves being in metallic contact with each other and with the cathode contacts will act as cathodes and receive the deposit.

From the construction and operation of the device set forth, it is thought that the advantages of the same should be readily apparent over similar devices heretofore used, and while I have herein shown and described one specific form of my invention, I do not wish to be limited to the details of construction thereof.

In Fig. IV of the drawings, I have illustrated a slightly modified form of agitating finger, in which the anode is directly secured thereto, as indicated at 18, so as to provide a compact and neatly appearing apparatus.

One of the most important features of the present apparatus is the provision of the rotating fingers or arms 15 which serve to agitate the electrolyte 8 and also the objects to be plated to cause a perfect diffusion of the electrolyte as well as providing supporting means for the cathodes. It will thus

be seen that the operation of plating will require a minimum of time and labor. It will also be understood that by providing the rotating fingers a high current is allowed to be used without burning or otherwise impairing the article so that the time consumed in the plating operation is again materially reduced.

From the foregoing description taken in connection with the accompanying drawings, it is thought that the operation of the apparatus should be clearly understood, and while I have herein shown and described one specific form of my invention I do not wish to be limited thereto except to such limitations as the claims may import.

I claim:

1. An electro-plating apparatus, including a stationary container for the articles to be plated, an electrolyte in the container, an anode in the electrolyte, and a movable non-conducting stirring member terminating in an exposed cathode contact for engagement with the articles to be plated to complete the circuit from the anode, 35

2. An electro-plating apparatus including a container having an electrolyte therein, a perforated container of a non-conductive material within said first container and disposed within the electrolyte, said second container being adapted to receive the articles to be plated, an anode, and a cathode movable within said second container, said cathode being adapted to contact and agitate said articles when being moved. 55

3. A device for the purpose described, comprising a receptacle of a non-conductive material containing a plating bath, a second receptacle of non-conductive material having perforations, means to support said second receptacle within said first receptacle, with a portion thereof in the bath, movable agitating fingers of a non-conductive material disposed within said second receptacle, an anode in said bath, cathodes on said fingers, and means for moving said fingers to agitate the bath and articles therein whereby said articles will be acted upon by the bath. 100

4. In an electro-plating apparatus, the combination with a container for the articles to be plated, and an electrolyte in the container, of an anode in the electrolyte and a movable stirring member having a plurality of agitating fingers of different lengths, said fingers being themselves insulated from the 115 electrical circuit of the apparatus but each terminating in a cathode contact, the several contacts being disposed at different distances from the center of movement and at different heights from the bottom of the container, 120 whereby most thorough agitation and contacting with the various articles is insured.

5. An electro-plating apparatus including a container in which an electrolyte is placed, a container of insulating material within 125

said first container in which the articles to be plated are placed, an anode, a cathode, and positive means for moving said cathode relative to the article whereby the articles 5 will be agitated and the electrolyte diffused.

6. An electro-plating apparatus including a container in which an electrolyte is placed, a relatively stationary perforated container within said first container, in which the 10 articles to be plated are placed, an anode, and a rotatable cathode for constantly engaging different of the articles to be plated whereby the electrolyte will act on all of said articles and whereby the electrolyte will be 15 diffused and the articles uniformly covered.

7. A device of the character described, including a receptacle having a peripheral flange or shoulder near the upper edge there-

of, a ring resting on said shoulder, a perforate container fitting centrally within the 20 ring and having an outwardly extending shoulder interlocking with the ring, whereby the perforate receptacle is suspended in the container by the ring, a cap plate fixedly carried by one of said parts, and a rotatable 25 stirring member carried by the cap plate and having exposed cathode contacts on the lower end thereof located within and near the bottom of the perforated receptacle, substantially as and for the purpose described. 30

In testimony whereof I affix my signature in presence of two witnesses.

HARVEY N. GILBERT
